UNITED STATES PATENT OFFICE.

LYMAN B. JORDAN, OF MALDEN, MASSACHUSETTS.

SASH-STOP.

SPECIFICATION forming part of Letters Patent No. 433,945, dated August 12, 1890.

Application filed February 24, 1890. Serial No. 341,573. (No model.)

To all whom it may concern:

Be it known that I, LYMAN B. JORDAN, a citizen of the United States of America, and a resident of the city of Malden, in the county 5 of Middlesex and State of Massachusetts, have invented certain new and useful Improvements in Window-Sash Stops, of which the following is a full, clear, and exact description.

This invention relates to a stop for sashes 10 of window-frames; and this stop is composed of a plate which is adapted to be fastened to the vertical rail of a sash, and of a spring-arm which at one end is hinged to one end of and extends along the length and over said plate, 15 and at its opposite end is free by pressure thereon to be moved toward and by its spring action to move away from the plate, and has a headed guide-pin arranged to play through a guide-opening of the plate and all otherwise 20 and applied to an upper sash and in combination therewith and the lower sash of a window-frame, substantially and to operate as hereinafter described.

In the drawings forming part of this specification, Figure 1 is a face elevation of a window-frame and its upper and lower sashes, which are both closed, and of the sash-stop applied to a vertical rail of the upper sash. Fig. 2 is a vertical section, line 2 2, Fig. 1. Fig. 3 25 is a face view, and Fig. 4 is an edge view, of the sash-stop enlarged. Fig. 5 is a similar view to Fig. 2, but on a reduced scale, and showing the sashes opened and the stop in action in relation to them.

30 In the drawings, A is the window-frame, and B and C the upper and lower sashes arranged to be moved up and down to open and close them, all as well known.

D D² is the sash-stop of this invention. 35 This sash-stop is composed of a plate D and a spring-arm D². The plate D is made of metal, in a sheet or other suitable form, but preferably of sheet metal, and at its opposite ends it has a hole a for the insertion of a screw to 40 fasten it in an upright position, end to end, on the vertical rail B² of the upper sash B. The spring-arm D² lies along the length of and at its upper end D³ it is held on the plate D, and its opposite end D⁴ is free, and preferably 45 50 it has a turn or bend b toward the plate D.

D⁵ is a pin held on the free end of the spring-arm D², and projected through a hole d of and to the opposite side of the plate, where it is headed, as at D⁶, to protect it against escape through said hole when the spring-arm 55 is opened from the plate, which is its normal position.

The sash-stop described is applied to a vertical rail of the sash with the free end of its spring-arm lowermost, and so placed the 60 spring-arm in its normal position and at its then lowermost end acts as a stop to the upward movement of the lower sash, enabling it to be left open to the height desired (which of course is determined by the height at which 65 said end of the stop is placed above the meeting-rails of the sashes when the sashes are closed) and without danger of being surreptitiously disturbed, and also preventing the opening of the upper sash to an extent greater 70 than that of the opening of the lower sash, as has been described. By sufficiently pressing the spring-arm D² toward the plate D the sashes can then be moved as ordinary. The 75 pin D⁵ of the spring-arm D² steadies the movement of the arm and further braces, stiffens, and protects it against being bent in case it should be attempted to force either sash beyond the limit to which they are confined by the stop.

Having thus described my invention, what I claim, and desire to secure by Letters Patent, is—

The combination, with the upper and lower sashes of a window, of a stop composed of a 85 plate D, held on a vertical rail of the upper sash, a spring-arm D² at its upper end held on and at its lower end normally open from said plate, a headed guide-pin D⁵, held on the free end of the spring-arm, and a hole d 90 through said plate D and receiving said pin D⁵, substantially as described, for the purpose specified.

In testimony whereof I have hereunto set my hand in the presence of two subscribing 95 witnesses.

LYMAN B. JORDAN.
